(57) **CLAIM**

I claim the ornamental design for a releasable fastening clip, as described and shown herein.

DESCRIPTION

FIG. 1 is a perspective view of a releasable fastening clip showing my new design. In this view, the fastening clip is shown in a closed position.

FIG. 2 is a front view of the fastening clip depicted in FIG. 1.

FIG. 3 is a back (or rear) view of the fastening clip depicted in FIG. 1.

FIG. 4 is a left side view of the fastening clip depicted in FIG. 1.

FIG. 5 is a right side view of the fastening clip depicted in FIG. 1.

FIG. 6 is a partial sectional view of the fastening clip depicted in FIG. 1 that is taken along the 6—6 line shown in FIG. 4.

FIG. 7 is a partial sectional view of the fastening clip depicted in FIG. 1 that is taken along the 7—7 line shown in FIG. 4.

FIG. 8 is a top (or plan) view of the fastening clip depicted in FIG. 1.

FIG. 9 is a bottom view of the fastening clip depicted in FIG. 1; and,

FIG. 10 is another perspective view of the fastening clip depicted in FIG. 1. In this view, the fastening clip is alternatively shown in an open (i.e., released) position.
